TOOL-HOLDING DEVICES

Albert Brittain Creed, London, England

Application November 19, 1956, Serial No. 623,175

Claims priority, application Great Britain
November 21, 1955

4 Claims, (Cl. 74—813)

This invention relates to tool-holding devices and more particularly to tool posts for use on lathes and for analogous purposes.

It is known to provide a tool post or tool box for a lathe in which provision is made to hold a plurality of tools and to rotate the tool post in order to bring any one of the tools into working position. Thus, for example a tool post may be of substantially rectangular shape and adapted to hold a tool in each side, the post being rotatable to bring each side and therefore each tool selectively into operative position. Such a device is known as an automatic indexing tool post.

It is, of course, necessary in such a device to provide means whereby the tool post may be locked very firmly in each of the selected positions. In one method an operating handle is provided which moves in one direction, usually anti-clockwise, will release the post so that it can turn and will cause engagement with, for example spring-loaded ball catches to cause the whole post to rotate to a next working position; the return motion of the handle is caused to lock the post in the selected position. The locking action may be achieved by arranging that the handle moves on a screw secured into the body of the lathe or to a slider on the lathe and when returned to its locking position exerts, by reason of that screw, a clamping action, the tool post being held between the body of the lathe or slider and the said handle. Since this does not afford a sufficiently rigid lock, however, proposals have been made to arrange that the movement of the handle to the locking position causes pins in the tool post to enter holes in the body or slider of the lathe and thus secure the post more rigidly. However, this method is not wholly satisfactory because not only is it necessary to provide holes in the lathe or slider with which the pins can mate (so that the assembly of the device is a matter for great precision) but the pins tend to wear and thus, in due course, permit a degree of movement of the tool post even when it is in the locked position.

The present invention provides a novel construction of tool post in which a positive lock is provided without requiring modification of the lathe in any way and which automatically compensates for wear in the working parts so that any tendency for the post to develop any freedom of movement, so-called "play," when in the locked position is reduced or eliminated.

A practical application of the present invention will now be described by way of example only with reference to the accompanying drawings whereof:

Fig. 1 is a side elevation of a tool post according to the invention,

Fig. 2 is an inverted plan of the tool post of Fig. 1, Fig. 3 is a section on the line III—III of Fig. 2, and Fig. 4 is a part-section in the line IV—IV of Fig. 2.

Referring to the drawings: the tool post comprises a body 5 which is rotatable about a threaded shaft 6 having a T-block or foot 7 for attachment to a lathe or other machine tool. The body 5 comprises a square

table 8 and a platform 9 carrying bolts 10 by which a tool 11 can be clamped to the table 8, one tool extending along each side of the table, i.e. there are four tool positions.

5 The shaft 6 extends through the body 5 (Fig. 3) and through the hub 12 of a hand lever 13 which is provided to rotate the body about the shaft for the tool-indexing purposes as later described.

The hub 12 is screw threaded, at 14, to the upper part 10 of shaft 6 and it is arranged that between a lower limiting position at which the hub engages body 5 and an upper limiting position at which it engages a nut 15 the hub is permitted one complete rotation only, i.e. corresponding to moving the four tools to their indexing positions.

The shaft 6 is integral with, or carries, a disc 16 having four equi-spaced abutments 17, the disc being received in a recess in the body 5. Each abutment has two faces, namely, a back face 27 and a front face 22. Said recess also receives a pivoted pawl 18 which is urged by spring 19 to engage the back face 27 of each abutment 17. Further, the body receives a pawl 20 which is urged by spring 21 to engage the front face 22 of each abutment. It will be noted from Fig. 2 that face 23 of pawl 20 and the face 22, with which the face 23 co-acts, are also inclined that there is a wedging action on engagement of said pawl with the face 22 under the force of spring 21.

Pawl 20 is pivotally carried by a rod 24 (Fig. 4) 30 which also carries an arm 25 lying within a recess in the upper part of the body 5. The hub 12 is formed with a polygonal, plate-like member 26 (in this instance a square plate) which is rotatable within the recess on adjustment of lever 13 as later described. The arm 25 engages member 26 so that upon rotation thereof the arm is pushed away from the member thereby to disengage pawl 20 from an abutment 17. The parts 24, 25 and 26 comprise the means for releasing the second pawl.

40 The body 5 has a pair of holes each of which receives a spring plunger 27, the plungers engaging opposite faces of the square member 26. The plungers permit limited movement of the hub 12 (and member 26) relatively to the body 5 whereupon the plungers reach the limit of their outward movement and the plungers then lock the member 26 to the body 5 so that with continued rotation of lever 13 the body is carried round with it. The limited relative movement permitted to member 26 is sufficient for said member to release pawl 20 from face 22 of abutment 17.

In use: when it is required to index the tool post the hand lever 13 is rotated (clockwise as seen in Fig. 2) and member 26 is turned relatively to body 5. Arm 55 25 engages a flat face of the member 26 and on such rotation the arm is carried outwardly so that pawl 20 releases face 22 of abutment 17. Thereupon with continued rotation of lever 13 the plungers 27 lock hub 12 to body 5 and the latter is carried round with the hub so that pawls 18, 20 ride past disc 16. When pawl 18 is brought past the next succeeding abutment 17 the pawl falls behind the back face 27 of the abutment. During this operation pawl 20 will have been continually held away from disc 16. The lever 13 is then rotated 60 in the opposite direction bringing pawl 18 tight against the abutment and releasing pawl 20 so that the latter engages the front face 22. Due to the wedging action of pawl 20 and the face 22 the abutment is firmly held and thus the indexing operation is accurately performed.

65 As wear occurs between the pawls 18, 20 and the faces 22, 27 this is automatically taken up by the wedg-

ing action of the abutment 22 and face 23 so that backlash and play is eliminated.

It will be appreciated that substantial variations may be made in the foregoing specific structure within the scope of this invention, such alternative apparatus including essentially the co-operating "wedging" and "locking" pawls as herein described. Thus, any alternative means of causing the movement of the handle to engage to move the tool box may be employed, for example spring-loaded plungers or the like. Moreover, the handle may be substituted by a control wheel, the tool box may have only two or three or may have more than four working positions and any alternative means may be adopted for releasing the "wedging" pawl.

I claim:

1. A tool post comprising a body, a fixed threaded shaft about which the body is rotatable for tool-indexing purposes, means for rotating the body about the threaded shaft, an abutment on said shaft for each tool-indexing position each of said abutments having two faces, a first pawl to engage one face of each shaft abutment to lock the body against rotation in one direction, a second pawl to engage the other face of each shaft abutment to lock the body against rotation in the opposite direction and means for releasing the second pawl to permit tool indexing rotation of the body, the co-acting surfaces of the second pawl and each of said other faces of the abutments being so inclined that there is a wedging action on engagement of the second pawl and the abutments.

2. A tool post comprising a body, a fixed threaded shaft about which the body is rotatable for tool-indexing purposes, means for rotating the body about the shaft, an abutment on the shaft for each tool-indexing position each of said abutments having two faces, a first pawl to engage one face of each abutment to lock the body against rotation in one direction, a second pawl to engage the other face of each shaft abutment to lock the body against rotation in the opposite direction, means for releasing the second pawl to permit tool-indexing rotation of the body and an inter-connection between said releasing means and said body-rotating means which ensures that the releasing means is actuated before the rotating means, the co-acting surfaces of the second pawl and each of said other faces of the abutments being so inclined that there is a wedging action on engagement of said second pawl and said abutments.

3. A tool post comprising a body, a fixed threaded shaft about which the body is rotatable for tool-indexing purposes, means for rotating the body about the threaded shaft, said means comprising a rotatable, polygonal, plate-like member and a pair of plungers spring-urged to engage a pair of opposite faces of the member, said plungers being carried by the body, the arrangement

being that the plungers permit limited relative movement of rotation of said member and thereafter lock the member to the body, an abutment on the threaded shaft for each tool-indexing position each abutment having two faces, a first pawl to engage one face of each abutment to lock the body against rotation in one direction, a second pawl to engage the other face of each of said abutments to lock the body against rotation in the opposite direction, means for releasing the second pawl to permit tool-indexing rotation of the body and an inter-connection between said releasing means and said body-rotating means which ensures that the releasing means is actuated before the rotating means, the co-acting surfaces of the second pawl and each of the other faces of the abutments being so inclined that there is a wedging action on engagement of the said pawl and said other face of the abutments.

4. A tool comprising a body, a fixed threaded shaft about which the body is rotatable for tool-indexing purposes, means for rotating the body about the threaded shaft, said means comprising a rotatable, polygonal, plate-like member and a pair of plungers spring-urged to engage a pair of opposite faces of the member, said plungers being carried by the body, the arrangement being that the plungers permit limited relative movement of rotation of said member and thereafter lock the member to the body, an abutment on the threaded shaft for each tool-indexing position each abutment having two faces, a first pawl to engage one face of each abutment to lock the body against rotation in one direction, a second pawl to engage the other face of each abutment to lock the body against rotation in the opposite direction and an arm for rotating said second pawl and said arm engaging the polygonal member and being adjusted thereby to release the second pawl from the other faces of said abutments during said limited relative movement of the polygonal member, the co-acting surfaces of the second pawl and of the other faces of said abutments being so inclined that there is a wedging action on engagement of said pawl and said other faces of the abutments.
